GARMENT PRESSING MACHINE

Walter A. Hoch, Forest Hills, N. Y., assignor to
 New York Pressing Iron Company, Inc., New
 York, N. Y., a corporation of New York

Application December 24, 1940, Serial No. 371,528

2 Claims. (Cl. 121—38)

My invention relates to a new and improved pressing machine.

One of the objects of the invention is to provide a power-actuated machine for pressing garments, having an improved two-hand control and improved means for holding the press closed under pressure, if the two-hand control is released after the press-head has moved a predetermined distance towards the buck.

Another object of the invention is to provide a pressing machine which is operated by a suitable motor, such as a piston and cylinder, and having improved means which are wholly independent of a by-pass valve or valves for maintaining the pressure, after the head of the press has been substantially or wholly closed.

Another object of the invention is to provide a machine of this type, wholly independent of a by-pass valve or valves, whereby the machine will be opened if the operator releases one or both of the manual controls, before the machine has been substantially or wholly closed.

Another object of the invention is to provide a machine of this type having improved exhaust means for opening the press, after the pressing operation has been completed.

Another object of the invention is to provide a machine having a minimum number of parts and which will be simple to construct and to operate.

Another object of the invention is to provide an improved control system whereby one operator may operate a single press or operate a plurality of presses.

Other objects of my invention will be set forth in the following description and drawings which illustrate certain preferred embodiments, it being understood that the above statement of the objects of my invention is intended generally to explain the same, without limiting it in any manner.

This application is a continuation in part of application Serial No. 292,761, filed August 31, 1939.

Figure 1 is a diagrammatic view of the control system which is used in connection with a press.

Fig. 2 illustrates a different position of the control valve which is shown in the upper part of Fig. 1.

Fig. 3 illustrates a different position of the lower valve which is shown in Fig. 1.

Fig. 4 shows the embodiment of Figs. 1-3 as applied to tandem-operated presses.

Fig. 5 is a top plan view of the table of the tandem-operated presses, according to Fig. 1.

Fig. 1 shows the pipe 90, which has one end thereof connected to the outlet side of the valve-casing 36. The other end of the pipe 90 is connected to the head 91 of the valve-housing 92. A plunger or valve-spindle 93 fits snugly but slidably in the respective bore of the valve-housing 92. This plunger 93 has respective heads 94 and 95. A compression spring 96 normally maintains the head 95 in contact with the flexible diaphragm 97. The diaphragm 97 has its periphery clamped between the head of the housing 92, and a supplemental rigid clamping head 98. The pipe 99 has one end thereof connected to a bore of the head 98. The other end of pipe 99 is connected to the port 56a of the operating cylinder 29. The port 59a at the inlet end of the cylinder 29 is connected by the pipe 100, to the valve-housing 101. A cross-pipe 102 connects the pipe 100 to the exhaust pipe 103, which is also connected at one end thereof to the valve-housing 92. The other end of the exhaust pipe 103 is connected to the valve-housing 104. This is provided with a valve 105 which is held in normally closed position by the compression spring 106. The lever 107 can be turned clockwise by hand in order to move the spindle of valve 105 downwardly so as to depress valve 105 from the closing position which is shown in Fig. 1, so that the air can pass through the outlet pipe 108 to the atmosphere. The pipe 103 is connected by a cross-pipe 109 to the head 110 which is rigidly secured to the valve-housing 101. A flexible diaphragm 111 has its periphery clamped by head 110, to the corresponding enlargement or integral head of the housing 101. The other end of the housing 101 is sealed by a removable plug 112. The valve spindle 114 has valve-heads 115, 116 and 117. This valve spindle 114 fits loosely in the bore 125a of the housing 101. The spindle 114 fits closely but slidably in the other bore of housing 101. A compression spring 118 normally maintains said heads 115, 116 and 117, in the normal positions illustrated in Fig. 1.

The air-inlet pipe 32 is connected by a cross-pipe 119 to the port 120 of the valve-housing 101. The connection between the cross-pipe 109 and the port 120 is through a coupling 121, which has a fine bore 122, whose cross-section is much smaller than the cross-section of the pipe 119. The function of coupling 121 is similar to the function of coupling 60, namely, to retard the flow of air through pipe 119. The cross-pipe 102 is also provided with a coupling 123, whose fine bore 124 is of much smaller cross-section than the pipes 102 and 103, etc., for the purpose above

mentioned. In order to close the press, the buttons 43 and 43a are simultaneously depressed and held down so that compressed air can pass through the pipes 32 and 33, through casing 34 and pipe 35 and casing 36, to pipe 90. Since the manually operated valve 105 is normally closed, namely, in the position shown in Fig. 1, compressed air will be delivered to the pipes 103 and 109, thus flexing the diaphragm 111 to the position shown in Fig. 2, thus moving the valve spindle 114 against the force of the spring 118. In the normal position shown in Fig. 1, the head 117 closes the respective end of the bore 125a of the housing 101. During the short interval which is required for moving the head 116 from the normal position indicated in Fig. 1 to the position indicated in Fig. 2, there will be some slight leakage of air through the pipe 102 and through the bore 125a, to the external atmosphere, through the pipe 125 and the noise-muffler 127. However, this leakage of air will be very slight, because the head 116 quickly closes the respective end of the bore 125a, and the coupling 123 limits the flow of air through pipe 102. When the spindle 114 has been moved to the position shown in Fig. 2, the compressed air will pass from the branch pipe 119, through the bore 125a, to the pipe 100 and to the port 59a, thus moving the piston 28 outwardly on its power stroke to close the press.

As soon as the piston 28 moves outwardly on its power stroke, the air is compressed above atmospheric pressure in the cylinder 29, forwardly of the piston 28, because the leakage of air through the casing of the needle valve N is controlled, in order to limit the speed at which the press is closed. However, the needle valve N is regulated, so that said air pressure will not operate diaphragm 97 from its normal position, against the force of spring 96.

In the embodiment of Fig. 1, when buttons 43 and 43a are held depressed, compressed air passes from the inlet pipe 32, through pipe 33, casing 34, pipe 35, casing 36, pipe 90, the chamber in which valve 94 is located, pipe 103 and pipe 109, to the chamber in which diaphragm 111 is located. Said diaphragm 111 is flexed to the position shown in Fig. 2, so that valve 117 is moved away from its seat, and valve 116 is moved to abut its seat. Compressed air passes simultaneously from pipe 32 through pipe 119 and the constricted coupling 121, to the chamber in which valve 117 is located. However, the area of diaphragm 111 is sufficiently greater than the area of valve 117, and the constricted coupling 121 sufficiently limits the flow of air into the chamber in which valve 117 is located, so that the diaphragm 111 can move spindle 114 to the position shown in Fig. 2.

The compressed air can then flow through the chamber in which valve 117 is located, and through the bore 125a and through pipe 100, into the inlet port 59a of the cylinder 29. The flow of air from pipe 103 through pipe 102 into pipe 100, is limited by the constricted coupling 123. The seated valve 116 prevents the air from exhausting through pipe 125. The seated valve 105 prevents the air from exhausting through outlet 108.

If the operator releases one of the buttons 43 or 43a, before the piston 28 has moved to the broken-line position in which said piston clears the port 56a, the flow of compressed air through casings 34 and 36 into pipe 90, is stopped.

The press is not closed, until the piston 28 has passed forwardly beyond and cleared the port 75

56a. Before the press has closed, it is sometimes necessary to stop the operation of the press and to open the press, in order to straighten out a wrinkle or to do other work on the garment. In order to work on the garment, the operator must release one or both of the buttons 43 and 43a. Upon releasing one or both of the buttons 43 and 43a, the further admission of compressed air to the pipe 90 is discontinued. Likewise, the compressed air in said pipe 90 can then leak out to the atmosphere, through the outlet pipe 36a or 34a. The compressed air in the pipe 90 then also leaks through the pipe 90 to the atmosphere, so that the diaphragm 111 is restored to its normal original position which is shown in Fig. 1. This shuts off communication between pipes 119 and 109. The air which is behind cylinder 29 in the piston 28 then leaks out to the atmosphere through the pipe 100 and through the bore 125a of valve-housing 101 and pipe 125 and the muffler 127 and also through the cross-pipe 102 and through the chamber of the valve-housing 92 and out through the pipe 90.

Therefore, the press is automatically opened by its conventional opening springs, if one or both of the buttons 43 and 43a are released, before the press is completely closed.

When the piston 28 has passed rearwardly beyond the port 56a, the full air pressure is maintained in the pipe 99, thus maintaining the diaphragms 97 and 111 in the respective positions shown in Figs. 3 and 2. The valve 94 then shuts off communication between pipe 90 and housing 92. If buttons 43 and 43a are released, said diaphragms are maintained in their operated positions shown in Figs. 2 and 3, so that the air cannot leak out of the cylinder 29 in front of piston 28.

After the pressing operation has been completed, the lever 107 is turned clockwise so as to move valve 105 downwardly against the force of spring 107, thus opening said valve 105. This exhausts the air from pipes 109, 103, 102, 100, and the chamber 92a, in which head 94 is located. When valve 105 is depressed, the compressed air is rapidly exhausted from pipe 109, because this has no construction. The diaphragm 111 is therefore rapidly restored to its normal position, so that the compressed air can rapidly leak out through pipe 100, bore 125a, pipe 125 and muffler 127. The area of diaphragm 111 exceeds the area of valve 117. Diaphragm 111 is located in a chamber which is sealed from bore 125a, by the close fit of spindle 114 in the bore of housing 101, which is directly adjacent the chamber in which diaphragm 111 is located. Hence, when the pressure upon the outer face of diaphragm 111 is released, the pressure of the air in said substantially enclosed chamber, and the force of spring 118, moves the spindle 114 to the normal position which is shown in Fig. 1. The loss of compressed air through pipe 119 is limited by coupling 121. Diaphragm 97 will also be rapidly restored to its original position, before the piston 28 has moved in front of port 56a. Hence diaphragms 111 and 97 will be restored substantially simultaneously to their original positions.

Since the spindle 93 fits snugly in the bore of housing 92, compressed air cannot pass from chamber 92a to chamber 92b.

In Fig. 4, the left-hand machine may be designated as machine No. 1, and the right-hand machine may be designated as machine No. 2. The casing of lever 81 of Fig. 4 is connected by pipe 89 to the casing 104 of machine No. 2. The

casing of lever 83 of Fig. 4 is connected by pipe 85 to the casing 104 of machine No. 1.

As shown in Fig. 5, each of the machines of Fig. 4 has a table which is provided with a pair of buttons 43 and 43a. The table of machine No. 1 of Figs. 4 and 5, is also provided with levers 81 and 107. When lever 81 is depressed, this exhausts the casing 104 of machine No. 2, thus opening machine No. 2, even though lever 107 of machine No. 2 is in its normal position. When lever 107 of machine No. 1 is turned, this exhausts the air from casing 104 of machine No. 1, thus opening machine No. 1. Machine No. 2 of Fig. 4 is provided with corresponding controls.

The embodiment of Fig. 1 has a first branch-line which includes the pipes 90 and 102, for supplying air to inlet-port 59a. This first branch-line has the first control valve 94. The embodiment of Fig. 1 also has a second branch-line for supplying air to inlet-port 59a, which includes pipes 119 and 100.

This second branch-line has the normally closed second control valve 117. The diaphragm 111 constitutes first fluid-operated pilot means to open the second control valve 117 and to maintain said valve 117 open, as long as said diaphragm 111 is connected to a source of fluid under pressure. Said diaphragm 111 is connected to the pipe 90 of the first branch-line. The diaphragm 97 constitutes second fluid-operated pilot-means which can close the first control-valve 94. Said diaphragm 97 is connected to the port 56a, which is located rearwardly of the cylinder-inlet 59a.

Whenever I refer to "means" in the claims, said designation includes one device or a plurality of devices.

Referring to Fig. 1, this shows a first inlet branch line which includes the pipe 90, and a second inlet branch line which includes the pipe 119. Each said branch line is connected, at the inlet end thereof, to the source 32, which delivers fluid under pressure. The outlet end of each said branch line is connected to the inlet port 59a. The first branch line, which includes the pipe 90, has a first valve 94 which is biased to normal open position by the spring 96. The second branch line, which includes the pipe 119, has a second valve 117 which is biased to normal closed position. The first pilot-means 111 is

connected to said first branch line and said member 111 opens the second valve 117, under the pressure in said first branch line. The second pilot-member 97 is adapted to close the first valve 94. Fig. 1 also shows means which include the pipe 99 and which are adapted to supply fluid under pressure to the member 97, when the piston 28 is moved forwardly a predetermined distance in its power stroke, so as to clear the port 56a. Fig. 1 also shows operator-controlled exhaust means which include the valve 105, for relieving both members 111 and 97 from the pressure of the fluid.

I have described preferred embodiments of the invention, but numerous changes and omissions can be made without departing from its spirit.

I claim:

1. In a press, the combination of a cylinder which has a piston located movably therein, the rear portion of said cylinder having a rear port through which fluid under pressure is admitted to actuate the piston in its forward power stroke to close the press, said cylinder having a second port which is located intermediate said rear inlet and the front end of the cylinder, said piston being located rearwardly of said second port when said piston is located at the rear end of its movement, a first inlet branch-line, a second inlet branch-line, each inlet branch-line being adapted to transmit fluid under pressure, each said branch-line being connected to said rear port, said first branch-line having a first valve which is biased to normal open position, said second branch-line having a second valve which is biased to normal closed position, first fluid-operated pilot-means connected to said first branch-line and adapted to open said second valve under the fluid pressure in said first branch-line, second fluid-operated pilot-means adapted to close said first valve, a pipe line which connects said second pilot-means and said second port, operator-controlled exhaust-valve means adapted to relieve both said pilot-means from fluid pressure.

2. A combination according to claim 1, in which the supply of fluid to said first branch-line is controlled through valve-casings which are located in series, each said valve-casing having a manually operated control-valve.
